Application October 17, 1934, Serial No. 748,589

7 Claims. (Cl. 108—7)

This invention relates to shingles and more particularly to the so-called composition shingles fabricated from composition roofing material and generally slate covered on their weather surfaces.

5 The invention relates not only to shingle construction, but also to the method of making the same.

The object of the invention is primarily to economize in the cost of manufacture and in 10 laying. The invention is particularly useful in this broad aspect in connection with the so-called strip shingles which embody an elongated strip of composition roofing provided at spaced apart distances along its weather edge with cut outs

15 forming between them tabs simulating wooden shingles. These so-called strip shingles are generally made from strip roofing of uniform width throughout its length and with the slots or cut outs formed along the weather edge as stated.

20 In laying roofing of this kind, it is common to lay the strips 4" to the weather and with, for example, a 6" overlap. Some roofers, however, lay such strips with as little as a 2" overlap and it is not uncommon for strips to be laid with a 25 2" overlap in the lateral direction, i. e., between cut outs. It is generally conceded that a 2" overlap on a roof with a fair degree of pitch is sufficient to exclude the entrance of water and to give a dry roof. Consequently, it is my view, 30 and I am borne out by practical demonstration, that the large degree of overlap provided in conventional strip shingles of uniform width is a waste of material.

I have discovered that it is possible in roofing 35 of this kind to effect a saving of approximately one-third of the material and still obtain a thoroughly serviceable roof and one which will properly exclude water. I accomplish this result by cutting shingles from a strip in a manner to overlap one another and by separating them by alternate transverse and castellated cuts, so arranged that I am able to obtain three strips out of the material heretofore required to yield two strips. I give these figures by way of example, 40 as proportions may be slightly varied without departing from the invention, but the said figures are illustrative of the material saving which may be accomplished in accordance with this invention.

45 50 Another feature of the invention relates to the manner of staggering the cut outs or slots at the weather edge of the shingle, in such a way as to give more pleasing effects on the roof and at the same time adapt the shingle of this invention for use as a strip shingle,

Another feature of this invention consists in a novel and efficient way of indicating either in whole or in parts the cut outs or slits at the weather end of the shingle, for I have discovered that I may make these so-called cut outs in a manner to appear as though they were cut out without actually cutting away the shingle. Similarly I am able to carry out this illusion either in whole or in part, that is to say I may cut for a part of the way and utilize the said illusion for the rest of the way. The advantage of this illusory practice is that it eliminates the relatively long tabs and thus eliminates flapping or curling thereof which features are outstanding objections in the art of composition shingles. 15

A further important feature of this invention is the utilization on a strip shingle of the type specified of a physical means for expeditiously and accurately gauging the overlap and simultaneously alining shingles as they are being laid 20 without the necessity of resorting to chalk lines, straight edges or the like. This means may further function as will hereinafter be fully explained to laterally space apart shingles of the same course, so that I obtain by the said means 25 a regulation of the overlap, proper longitudinal alinement and accurate lateral spacing, all of which are highly desirable in laying strip shingles.

Features of the invention, other than those 30 adverted to, will be apparent from the hereinafter detailed description and claims, when read in conjunction with the accompanying drawings.

The accompanying drawings illustrate different 35 practical embodiments of the invention, but the constructions therein shown are to be understood as illustrative, only, and not as defining the limits of the invention.

Figure 1 is a face view of a plurality of shingles laid in courses in accordance with the present 40 invention.

Figure 2 is a section on the line 2—2 of Figure 1.

Figure 3 is a section on the line 3—3 of Figure 1.

Figure 4 shows the manner in which the shingles of Figure 1 may be cut from roll roofing in a thoroughly efficient manner and without waste.

Figures 5 and 6 show complementary shingles cut from roll roofing, as shown in Figure 4.

Figures 7-11 are front views of shingles similar to those of Figures 5 and 6, but illustrating tabs of different shapes.

Figure 12 is a fragmental perspective showing the manner of forming the cut out of Figure 11. 55

Figure 13 is a similar view showing the manner of producing the effect of a cut out without weakening the shingle or actually forming a tab.

Figures 14 and 15 show different dispositions 5 of cut outs or tabs.

Figures 16, 17 and 18 show the manner of applying the illusory cut out arrangement, illustrated in Figure 13, in four-in-one, three-in-one and individual shingles, respectively.

10 In carrying out this invention in a strip shingle, I preferably proceed in the manner best illustrated in Figures 4-6 of the drawings. In other words, I start with roll roofing of a width which may be equal to the length of the shingle strip. 15 This roll roofing is designated in Figure 4 by the reference character 1. Working from the end of this strip, I cut the shingles therefrom utilizing alternately straight transverse cuts 2 with intermediate cuts of castellated shape 3 and with 20 the axis of symmetry of these castellated cuts spaced medially between the straight transverse cuts. At the same time while making these cuts, I may also simultaneously form the cut outs 4 which in practice may be mere slits or actual cut 25 outs of appreciable width, although in certain forms of the invention the cut outs may be extended for a part of the way and the material scored for the rest of the way or the material may be scored for the whole distance of the out- 30 lines of an illusory cut out as will be hereinafter more fully explained.

I may also, during the formation of the cuts 2 and 3, simultaneously produce additional cut outs or slits indicated at 5, 6 and 7 for alining and 35 spacing purposes, as will be presently explained in detail, but the feature to be borne in mind at this point is that I produce the transverse straight cuts with intermediate castellated cuts as stated. With this procedure, shingles fall 40 from the cutters in the complementary form shown in Figure 6, being formed in an inter-fitting manner and cut away from one another as shown in these two latter figures.

Both of these shingles are identical in form 45 and they are cut without waste and are adapted to cooperate with one another during laying. Each has a straight weather edge 8, while its upper edge is castellated. The widths of the several upper projections 9 are the same as 50 one another and also the same as the spaces 10 between them.

While the matter of specific dimensions is not particularly important other than the general relation between them, the following may be 55 given by way of example. If each strip is 36" long, the cut outs 4 may be made 4" long, the overall height of the strip may be made 10" and the depth of the castellations may be made 4". The castellations may be made 9" wide and the 60 spaces between them of a similar size. With this arrangement, the shingles may be conveniently laid with a minimum 2" overlap and will then give a perfectly tight roof.

These dimensions which have been given are 65 illustrative and are not intended to limit the invention as the strips may be made deeper if more overlap is desired. Nevertheless and in any event a very pronounced saving in material over the conventional strip is accomplished by this arrangement. In fact, figuring the material by the 70 running yard, a saving of approximately one-third of the material is effected without any real difference in the finished roof so far as exclusion of water is concerned. Such being the case, the 75 invention is of very pronounced importance from

the standpoint of economy of material and as will presently be explained, the shingles may be laid as easily and in fact more readily with proper alinement than the conventional strip shingle.

The manner of laying these shingles is shown 5 in Figure 1. They may be cut if desired without the alining devices 5, 6 and 7 and may be laid to a straight edge or to the slots or cut outs 4, as is usual in strip shingles, in which event, they are so positioned that successive courses break 10 joints between adjacent shingles at the high parts of the underlying shingles, so that a high portion of each underlying shingle underlies each joint between shingles of the overlying course as will clearly appear from Figure 1. It is of course 15 essential also that the slots or cut outs 4 overlie the high portions of the underlying shingles, so as to preclude leakage through proper overlap, and Figure 1 shows how this may be accomplished. In order to obtain these results care 20 should be taken in the design of the shingle strip, so that the cut outs 4 which form the end tabs of the strip will be located over the high parts of underlying shingles and as illustrated, I arrange these in pairs as shown, the cut outs being 25 placed alternately a lesser and greater width apart where a four tab shingle strip with three cut outs is desired.

A roof laid with shingles made in this way very closely simulates one laid with wooden shingles 30 for it has long been the practice in laying wooden shingles to lay a wide shingle then a narrow one, then a wide shingle, and so on. Thus the finished roofing more closely simulates a roof of wooden shingles and this is desirable because one 35 of the objections made to conventional strip shingles in the past is that there is too much sameness or uniformity in the size of the tabs.

I wish it understood, however, that this particular grouping of tabs may be varied without 40 departing from this invention and also that the shape of the tabs resulting from the shape of the cut outs 4 may be changed within the scope of this invention. For example, in Figure 7, the cut outs 4a are shown as curved at their lateral edges 45 to produce rounded tabs, while in Figure 8 the cut outs 4b are beveled at their lateral edges, so as to produce tabs with cut out off corners simulating hexagonal shapes. Similarly, the cut outs 4c of Fig. 9 or 4d of Fig. 10 may be arranged 50 otherwise in perpendicular with respect to the weather edge 8 of the strip, these two latter figures showing them inclined in opposite directions.

It should also be borne in mind that a lesser 55 number of cut outs with a corresponding less number of tabs may be provided as shown, for example, in Figure 14, where only two cut outs 4e are provided, while in Figure 15 only one cut out 4f is formed in the strip, so as to divide the strip into two wide tabs of the same width. 60 These and similar changes from the construction shown in Figures 1-6 are within the scope of the present invention.

The present invention also includes means for 65 insuring proper laying of the shingles of each course, so that the cut outs 4, 4a, etc., may be made to automatically register with the high parts of shingles of the next underlying course and thus make it unnecessary for the workmen to exercise care in the placement of the shingles. This 70 means consists in forming in the upper edge of the high portion 9 of the shingle strip adjacent one end of the shingle a gauging device shown in the form of the cut out or slit 7. This cut out or slit may be of any appropriate shape, so long 75

as it will form an abutment or stop for the lateral edge of a shingle of an overlying course. For convenience, however, I preferably use a cut out 5 of substantially right angular shape as shown, so as to form from the body of the strip a tongue 11 facing in a direction away from the adjacent lateral edge of the strip and this tongue is so positioned that the corresponding lateral edge of an overlying strip may be engaged with the 10 tongue, as shown in Figure 1, to properly position the strip longitudinally with respect to such overlying course and with respect to the corresponding underlying course to break joints and position the cut outs 4 in the manner hereinbefore described. Merely the edge of the overlying strip may be engaged, although I preferably notch such overlying strip at its lateral edge as indicated at 15 5 to receive the hook or tongue 11 and so position the notch 5 that when engaged with the tongue 10 the proper lap between the two shingles will result. In this way, I am not only able to obtain the desired lateral spacing of each individual shingle with respect to the underlying shingle, in order to break joints between courses, but at the 20 same time I obtain the proper lap. Furthermore, in order to obtain proper longitudinal alinement and to insure uniformity of the lap for the full length of the shingle strip, I provide at the upper edge of the strip and at the base of one of the 25 castellated spaces 10 a stop or abutment 6 preferably in the form of a slot or cut out and preferably L shaped to provide a tongue 12 and directly above the notch 5 at the upper corner of the strip, I form another notch 14 to be engaged by 30 the tongue 12, as shown in Figures 1 and 3. By this arrangement, I not only preserve longitudinal alinement with uniform overlap, but at the same time I laterally space apart adjacent shingles of the same course and I accomplish this in 35 a mechanical way and without requiring any figuring or thought on the part of the roofer. In laying the shingles he simply lays the first course straight and with proper spacing, and thereafter the shingles of the next course are simply 40 hooked into place and proper alinement, lateral spacing and accurate overlap are bound to result. He cannot go wrong or make a mistake.

The features of the invention which I have just described with relation more particularly to the 45 alining and spacing devices are by preference collectively incorporated in the shingle of this invention where they all cooperate to facilitate and expedite laying a shingle of pronounced economy in materials, so that there results not only an 50 economy in material, but ease and economy in labor costs for laying the same. I am aware, however, that certain of these devices might be used to marked advantage without necessarily employing them all and the invention in this regard is to be understood as not limited to the 55 employment of all, but as commensurate with the appended claims.

In the foregoing detailed description, reference has been made to cut outs 4, 4a, etc., which 60 have been referred to as susceptible of various shapes and numbers. I have also discovered, however, that I may obtain the effect of cut outs without necessarily forming them, either in part or in their entirety. The real purpose of cut 65 outs is, in practice, to give the appearance of conventional wooden shingles on a roof, i. e., to break up the monotony which will result in the laying of continuous edge strips. The cut outs are mechanically the source of considerable annoyance as the tabs tend to curl and flap in 70

heavy winds, but they have nevertheless been used because of the failure to find anything better for the purpose.

In Figures 11 and 12, however, I have shown means whereby the visual effect of the cut out 5 may be obtained without the mechanical defects referred to. Here each of the cut outs 15 is made much shorter than usual and for the remainder of the distance for which the cut out would ordinarily be made, the lateral edges of the tabs 10 are scored, as shown, at 16 with deep lines of scoring which serve to outline the area normally occupied by the cut out. The lines of scoring remove the slate from the surface of the shingle at the edges of the tab areas, so that when the 15 shingle is laid on a roof, it appears from a distance as though the slot or cut out 15 extended for the full length of the tab instead of for only part of the way. Nevertheless, the actual cut outs are relatively short, so that the projecting 20 portions of the tabs are correspondingly short and will not appreciably curl or flap.

The structure of Figures 11 and 12 may be carried out with cut outs of any shape without departing from this invention and while scoring 25 has been referred to as the preferred way of producing the lines 16, they may be produced in any other suitable way, so long as the slate is absent along these lines, but is present within the uncut away portion of the slot area and beyond the edges of the slot area. The line 16 should be sufficiently wide and deep to be clearly visible and to produce a different color effect or shadow when laid on a roof. My experience has been that mere scraping away from the slate 30 down to the material forming the body of the shingle will suffice for this purpose.

A very satisfactory modified form of arrangement is also shown in Figure 13. Here no cut outs whatever are provided in the edge of the 40 strip, but the lines of scoring 16 are utilized exclusively to define the cut out portion. When these shingles are laid on a roof, the visual effect of the cut out is present, but the mechanical disadvantages are absent. A marked advantage of 45 the structures of Figures 12 and 13 is that a shingle made with short cut outs or none may be laid with much less overlap with corresponding economy than a shingle actually having a cut out and the fact that the slate surface is left 50 within the area bounded by the lines 16 and which constitutes the normally cut out portion of the shingles overcomes that solid black or other undesirable solid color effect which would result if the slate were removed from this part. When 55 the slate is wholly removed from the portion which corresponds to the cut out, it produces on a roof the effect of the cut outs having been painted and is objectionable for this reason. The arrangement as shown will last throughout the 60 life of the shingle and will continue to be neat and pleasing in appearance as well as continue to be free from the mechanical objections heretofore pointed out as prevalent in conventional strip shingles.

The production of illusory cut outs as described may be carried out in strip shingles as shown in Figures 11, 16 and 17 in which four-in-one, and three-in-one strip shingles are shown, and it may be also utilized in connection with so-called two-in-one strip shingles or in connection with individual shingles as shown in Fig. 18.

The foregoing detailed description sets forth the invention in its preferred practical forms, but for the reasons hereinbefore given, the in- 75

vention is to be understood as commensurate with the appended claims.

The shingle of this invention is intended to be made particularly from composition roofing material, but it may be made from asbestos, metal or any other material.

Having thus fully described the invention, what I claim as new and desire to secure by Letters Patent is:

1. As a new article of manufacture, an elongated strip of roofing material having a longitudinal weather edge and the opposite longitudinal edge of the strip shaped to form consecutive portions of the length of the strip into alternately wide and narrow parts, so that the strips may be laid in successive courses to break joints over the wide parts of underlying strips, said strip being provided at the upper edges of one of its wide parts and one of its narrow parts with tongues 20 to facilitate laying of a plurality of said shingle strips in courses.

2. A shingle strip comprising an elongated strip of roofing material, one longitudinal edge of which constitutes the weather edge and the other longitudinal edge of which is castellated to form the length of the shingle into alternate wide and narrow parts, one wide part being provided adjacent its upper edge with an abutment and at its lateral edges with notches and one of the narrow parts of said strip being provided adjacent its upper edge with an abutment, said abutments being adapted to cooperate with the corresponding notches in other shingles of the same kind during laying to give predetermined alignment, overlap and longitudinal spacing.

3. A shingle strip comprising an elongated strip of roofing material, one longitudinal edge of which constitutes the weather edge and the other longitudinal edge of which is castellated to form the length of the shingle into alternate wide and narrow parts, one wide part being provided adjacent its upper edge with an abutment and at its lateral edges with additional abutments and one of the narrow parts of said strip being provided adjacent its upper edge with another abutment, the abutments adjacent the upper edge of said strip being adapted to cooperate with the abut-

ments of other shingle strips of the same kind during laying to insure the breaking of joints between strips of one course with strips of the underlying course at such points that each joint will overlie a wide part of the underlying strip. 5

4. A shingle strip comprising an elongated strip of roofing material, one longitudinal edge of which constitutes the weather edge and the other longitudinal edge of which is castellated to form the length of the shingle into alternate wide and narrow parts, one wide part being provided adjacent its upper edge with a hook shaped tab and at its free lateral edge with notches, and one of the narrow parts of said strip being provided adjacent its upper edge with another hooked tab, 15 said hooked tabs being adapted to cooperate with the notches of other strips of the same kind during laying to insure the breaking of joints between strips of one course with strips of the underlying course at such points that each joint 20 will overlie a wide part of the underlying strip.

5. A strip shingle comprising an elongated strip of slate surfaced composition roofing material having relatively short cut outs extending into the body of the strip from the weather edge 25 thereof, the slate surfacing of the material being removed along lines defining the edges of each cut out in a direction constituting continuations of said cut out for a distance beyond the end of the cut out leaving the slate surfacing in 30 the zone bounded by said lines to give the appearance of a cut out of increased length when a plurality of these shingles are laid on a roof.

6. A shingle of slate covered composition roofing material having a weather edge, the slate 35 surface of said shingle being removed along predetermined lines extending from the weather edge to outline the zone of a cut out, leaving the greater portion of such zone with its slate covering to give the effect of actual cut outs when a plural- 40 ity of these shingles are laid on a roof.

7. A slate covered shingle of composition roofing having a cut out portion simulated by lines defining the outlines of said portion and bare of slate covering, while the surface of the shingle 45 at both sides of said lines is slate covered.

HARRY H. HONIGBAUM.
